UNITED STATES PATENT OFFICE.

CHARLES C. HEYDER, OF HANSFORD, WEST VIRGINIA.

ELECTRIC HEATER.

1,061,289.

Specification of Letters Patent.

Patented May 13, 1913.

Application filed August 31, 1912. Serial No. 718,083.

To all whom it may concern:

Be it known that I, CHARLES C. HEYDER, a citizen of the United States, residing at Hansford, in the county of Kanawha and 5 State of West Virginia, have invented new and useful Improvements in Electric Heaters, of which the following is a specification.

This invention relates to electric heaters and more particularly to that type which is 10 adapted to heat cauteries or like instruments.

One of the principal objects of the invention is to construct the heating unit in such a manner that it is separable from its inclosing casing so that should one of the coils 15 burn out the entire heating unit may be removed from the casing and the damage repaired or a new unit substituted.

Another object of the invention is the provision of a simple and efficient device of this 20 character which may be cheaply constructed and which will be durable and convenient to handle.

Further objects of this invention will appear as the following specific description is 25 read in connection with the accompanying drawing which forms a part of this application, and in which:—

Figure 1 is a perspective view of the device showing a cautery point arranged there- 30 in. Fig. 2 is a similar view with parts broken away and with the heating unit removed. Fig. 3 is a side elevation of the heating unit with parts broken away. Fig. 4 is a detail vertical sectional view through 35 the device.

Referring more particularly to the drawings 1 represents a base having secured there- 40 upon by means of the screws 2 a rectangular shell or casing 3 which is closed at its upper end by a lid or cover 4 provided with a plurality of apertures 5 for a purpose to be hereinafter described. The lid or cover 4 is 45 also secured upon the casing by means of screws 6 so as to be readily removable when it is desired to remove the heating unit to be hereinafter described. Leading into the casing are the terminal pins 7 which are insulated therefrom by the bushings 8 and have connecting to their inner ends suitable contact springs 9 arranged in parallelism above the base 1 which is preferably of insulating material.

The heating units comprise point or instrument receiving tubes 10 constructed of 55 any suitable dielectric material by prefer-

ably having high heat conducting qualities. These tubes have spirally wound around the same a wire 11 of high electrical resistance in the form of heating coils whose terminals are connected at one end thereof and at the 60 opposite end are secured to contact points 12 arranged in position to engage the springs 9. The coils and their supporting tubes are embedded in a block of insulating material 13 which fits the interior of the casing 3 and 65 is held in position with the terminals 12 in engagement with the springs 9 by means of the cover 4. The pins 7 are so arranged with respect to each other as to make connection with a coupling socket carried by a flexible 70 conductor which may be connected in the ordinary incandescent lamp circuit.

Secured to the casing and to the base is a manipulating handle 14 by which the heater may be carried from point to point.

The holes 5 in the cover register with the tubes 10 so that cautery points may be inserted into the tubes and allowed to remain therein while the current is on until fully heated.

75

What is claimed is:—

1. A heater comprising a metallic casing, contact terminals carried by but insulated from the casing, spring contacts connected to the terminals and extending into the casing and insulated heating coils removably mounted in the casing and having their terminals arranged to engage said spring contacts together with an apertured cover for holding the coil terminals in engagement 80 with the spring contacts.

2. An electrical heater comprising a casing, contact terminals connected to but insulated from the casing, contact springs carried by the terminals and extended into the 95 casing, instrument receiving tubes, heating coils surrounding the tubes, an insulated block covering the tubes and the coils and having the terminals of the coils projecting therefrom to engage the springs and a cover 100 removably secured on the casing for holding the terminals of the coils in engagement with the springs, said cover being apertured to register with the instrument tubes.

In testimony whereof I affix my signature 105 in presence of two witnesses.

CHARLES C. HEYDER.
